10 The drawing shows in perspective a chair embodying my new design.

My design is herein confined to the back of the chair; and it consists, essentially, in a curved paneled top piece, a curved bottom 15 piece, and an intervening frame fixed in position by rounds. The frame *f* is 20 rectangular in shape, and is provided with a beaded or ornamented edge, *g*. The frame *f* is located between the top piece, *a*, and bottom piece, *d*, and retained in position by two series

of rounds, *h i*. The frame *f* is provided internally with cane splints *m*, suitably interwoven 25 to present to the eye a cane back for the chair.

I claim—

1. In a design for chair-backs, the curved paneled top piece, the curved bottom piece, and the intervening cane frame fixed in position between said top and bottom pieces by 30 rounds, as set forth.
